H. D. PRATT
SCRAPER.
APPLICATION FILED JAN. 26, 1918.

Patented May 14, 1918.

Inventor,
Howell D. Pratt,
by his Attorneys,
Johnson & Johnson

UNITED STATES PATENT OFFICE.

HOWELL D. PRATT, OF PHILADELPHIA, PENNSYLVANIA, ASSIGNOR TO LINK-BELT
COMPANY, OF CHICAGO, ILLINOIS, A CORPORATION OF ILLINOIS.

SCRAPER.

1,266,153.

Specification of Letters Patent. Patented May 14, 1918.

Application filed January 23, 1918. Serial No. 219,884.

To all whom it may concern:

Be it known that I, HOWELL D. PRATT, a citizen of the United States, residing in Philadelphia, Pennsylvania, have invented 5 certain improvements in Scrapers, of which the following is a specification.

One object of my invention is to construct a scraper for use in removing sand and other granular material from piles, and 10 particularly for feeding elevators with sand.

A further object of the invention is to construct the scraper so that it will not embed itself in the sand.

A still further object of the invention is 15 to provide means for guiding the scraper as it is drawn through the sand.

In the accompanying drawings:

Figure 1 is a perspective view of my improved scraper;

Fig. 2 is a diagrammatic view showing 20 the scraper in the act of removing a load of sand from a pile; and

Fig. 3 is a transverse sectional view on 25 the line 3—3, Fig. 2.

1 is the Scraper made of sheet metal having a solid top Section 2. A curved end 3 forms a scoop or bucket. 4, 4 are the side runners which, in the present instance, are in the form of plates and extend to a depth 30 equal to the depth of the curved scoop 3, and these runners form the side walls of the scoop and are rounded at the front end, as clearly shown in Fig. 1. The top section has a curved lip 5 at the front end which 35 prevents the sand from passing over the top of the scraper.

I secure a T or angle iron 7 on the top of the scraper and secure a hauling rope 6 to this iron, so that the weight of the scraper 40 will always be below the draft line, and the scraper when free of the sand will always have a tendency to right itself so as to properly dig into the sand for another load. By rounding the back of the scoop 3 of the 45 scraper, as shown, the scraper will readily ride over the sand as it is returned for another load. I preferably make the scoop end 3 comparatively short so that the sand will not pack in the space between the lower edge of the scoop and the top plate.

The hoisting rope 6 is attached to any

suitable windlass for the purpose of dragging the scraper over the surface of a sand pile, such as shown at x. In the present instance, this sand pile is in close proximity to an elevator 10 having the ordinary buckets 8. The sand flows into the boot 9 of this elevator by gravity as it is carried forward by the scraper 1.

While the scraper is made of sheet metal, 45 as illustrated in the drawings, it can be made of any suitable material and braced in any suitable manner, depending upon its capacity. The ordinary scraper has a tendency to dig into the sand to a greater depth 50 than desired and, consequently, more power is used than is necessary, but by making the scraper in the manner shown, with a flat top section 2, it is prevented from digging into the sand deeper than the depth of the 55 scraper, and by having the side runners, as shown, the scraper is held from taking a zigzag course and the draft is more even than if the runners were omitted.

I claim:

1. The combination of a scraper for removing granular material from a pile, consisting of a scoop section for engaging the material; runners forming the sides of the scoop and acting to guide the scoop as it passes through the material; and a top plate in advance of the scoop preventing the scraper digging into the pile to a greater depth than the scoop section.

2. The combination in a scraper, of a top 65 plate turned up at the forward edge; a curved scoop forming the rear plate and extending below the top plate; side plates forming the side walls of the scoop and extending toward the front end of the scraper, 70 curved at the front edge and forming guides or runners for the scraper.

3. The combination in a scraper, of top 75 and side plates having a scoop section at one end; and a bar mounted on the top of the scraper and to which the hauling ropes are attached, the bar being so located as to cause the scraper to right itself when tension is put on the rope.

In witness whereof I affix my signature. 100

HOWELL D. PRATT.
